(57) CLAIM

I claim the ornamental design for a tray for rolling cigarettes, as shown and described.

DESCRIPTION

FIG. 1 is a top perspective view of a tray for rolling cigarettes, showing my new design;

FIG. 2 is a bottom perspective view thereof;

FIG. 3 is a right-side elevational view thereof;

FIG. 4 is a left-side elevational view thereof;

FIG. 5 is a front elevational view thereof, the rear elevational view being a mirror image thereof;

FIG. 6 is a top plan view thereof;

FIG. 7 is a bottom plan view thereof; and,

FIG. 8 is an exploded top perspective view thereof.

1 Claim, 4 Drawing Sheets
